[57] **CLAIM**

The ornamental design for a shoe outsole, as shown.

DESCRIPTION

FIG. 1 is a right-side elevational view of the shoe outsole showing my new design. The broken line showing a shoe upper is for environmental purposes only and forms no part of the claimed invention;

FIG. 2 is a bottom plan view of the shoe outsole showing my new design;

FIG. 3 is a left side elevational view thereof;

FIG. 4 is a front elevational view thereof; and,

FIG. 5 is a rear elevational view thereof.
